Claims priority, application France Feb. 2, 1968

Term of patent 7 years

U.S. Cl. D48—24
Int. Cl. D26—99; D10—08

FIG. 1

FIG. 2

FIG. 3

FIG. 1 is a top rear perspective view of a combined headlamp and odometer showing my new design.

FIG. 2 is a bottom front view thereof.

FIG. 3 is a side view of FIG. 1, the opposite side being a mirror image thereof.

The numerals and other indicia are shown in broken lines for purposes of illustration only.

I claim:

The ornamental design for a combined headlamp and odometer, as shown and described.
